UNITED STATES PATENT OFFICE

JOHN D. IHLDER, OF YONKERS, NEW YORK, ASSIGNOR, BY MESNE ASSIGNMENTS, TO THE OTIS ELEVATOR COMPANY, OF EAST ORANGE, NEW JERSEY.

SPEED-CONTROLLER FOR ELECTRIC ELEVATORS.

SPECIFICATION forming part of Letters Patent No. 657,416, dated September 4, 1900.

Application filed November 27, 1897. Serial No. 659,973. (No model.)

To all whom it may concern:

Be it known that I, JOHN D. IHLDER, a citizen of the United States, residing at Yonkers, in the county of Westchester and State of New York, have invented certain new and useful Improvements in Speed-Controllers for Electric Elevators, of which the following is a specification.

My invention relates to a speed-controller for electric elevators, and has for its object to improve the construction and arrangement of parts whereby the speed of the elevator can be controlled; and it consists in the various features of invention having the general mode of operation substantially as hereinafter more particularly set forth.

In the accompanying drawings, Figure 1 is a diagrammatic representation of the circuits and devices embodying the invention; and Fig. 2 is a similar diagrammatic representation showing an additional feature of the invention, including the extra field-coil, as hereinafter explained.

While my invention is adapted more particularly for use in connection with electric elevators, it may be applied for other and different purposes, and the details of construction and arrangement of parts may be varied to adapt it for different circumstances without departing from the general features of the invention, and I am therefore not limited to the precise construction and arrangement of parts shown.

In the operation of electric elevators, especially in high-speed elevators, it is desirable to provide means whereby the speed can be controlled, and especially to provide means whereby the speed can be electrically controlled, so as not to have to depend upon the brake. It has been found that when the elevator is traveling rapidly and the switch is operated to stop the motor and the brake is applied the car may be caused to stop too quickly, causing a jolt or jar, which is unpleasant as well as liable to strain the apparatus, and one of the main objects of the present invention is to provide electrical means for producing a slow speed before the brake is necessarily applied. These means may be arranged in different ways, so as to be oper-

ated automatically by the usual automatic stop device, thereby slowing the speed of the car as it approaches the extremes of its movement in the well, or it may be operated from the car by the attendant at any point, as approaching landings or in case of emergency, and I will now proceed to describe the preferred embodiment of the invention.

In the accompanying drawings I have shown an arrangement of circuits on the general principles set forth in my Patent No. 560,216, granted May 19, 1896, in which M is the armature of an electric motor connected to operate the elevator winding-drum or other device. (Not shown.) A represents a shaft 65 which is adapted to be operated by the usual hand-ropes or other control device from the car, and connected to this shaft are the usual switches and pole-changer or current-reverser B. C represents a resistance device composed 70 in the present instance of a number of contact-plates c¹ c² c³ c⁴ c⁵ c⁶ c⁷ c⁸ c⁹ c¹⁰ c¹¹, with intermediate resistance-coils between the plates, except at their extremities and between the plates c⁵ c⁶. Connected to operate with 75 this resistance is a brush D, which is carried on a suitable lever-arm controlled in the usual way by mechanism connected with the shaft A and also further controlled in the present instance by an electromagnetic dash-pot E, as 80 more fully set forth in the patent above referred to. Also included in the armature-circuit is a potential switch F, illustrated diagrammatically, and while various constructions can be used I prefer to use a switch constructed substantially like that set forth in my Patent No. 594,879, dated December 7, 1897. Also arranged in the circuit is a stop-motion snap-switch G, which may be of any proper construction, but is preferably based on the 90 general principles of construction and operation set forth in my Patent No. 596,512, dated January 4, 1898. These mechanical features are not illustrated in details of construction, but are indicated diagrammatically sufficient 95 to enable their operations to be understood by those skilled in the art, and it is not deemed necessary to describe them in detail.

On the shaft A or connected to be operated thereby is an arm A', carrying contacts a'a', 100

connected together and also carrying on an extension of the arm and insulated from the others a contact a^2 , and arranged to coöperate with this arm are the contacts a^4 a^5 a^6 5 a^7 a^8 , these being typical only of the ordinary switch and sufficient to explain the present invention. It will be noted that the contacts a^4 and a^5 are electrically connected together, as are contacts a^6 a^7 , and it will further be 10 noted that contact a^8 is in the form of a segment, with its ends extended, so that when the arm A' is moved to the right or the left the contact a^2 will bear upon the segment-contact a^8 after contact a bears upon contact a^4 or a^5 , although the arm A' can be moved to a position to withdraw contact a^2 from contact a^8 and still retain contact with the plates a^4 a^5 , the purpose of which will be understood hereinafter. The circuit-reverser B is herein 15 typically represented as having two conducting-plates B' B'' , insulated from each other, and arranged around the plates are the brushes b b' b'' b''' .

In order that the invention may be best 20 understood, the circuits will now be traced, it being generally stated that to start the motor in either direction the shaft A is operated in one direction or the other from the elevator-car by the usual control devices, and 25 this closes the circuit through the motor in the proper direction to cause it to rotate to raise or lower the car, and at the same time the brush D , controlling the auxiliary resistance C , is released from mechanical connection, so that more or less of the auxiliary 30 resistance is cut out, depending upon the current flowing through the motor and controlled in the present instance by the electromagnetic dash-pot E , and when the arm A' is moved to its normal position (shown in 35 the drawings) the brush D is mechanically restored to the position shown, bearing on the contact-plate c . The lines plus and minus indicate the feeding-circuit for the motor, 40 and the current is supposed to enter by the conductor 1, extending to the binding-post H , and thence by the conductor 2 through the shunt field-magnet coils 3 of the motor M to the post H' , and thence by the conductor 40 4 out to the main line. Branching from conductor 1 is the conductor 5, leading to the connected contacts a^6 a^7 of the switch. The contacts a^4 a^5 on the opposite end of the switch are connected together, and from them 45 a conductor 6 leads to the contact f of the potential switch F , while connected to the lever F' of the switch normally bearing on said contact is a conductor 7, leading to brush b , and from brush b' is a conductor 8, leading 50 to the binding-post I , which is connected by conductor 9 to the brush m of the armature, while the brush m' is connected by conductor 10 to the binding-post I' , which in turn is connected by conductor 11 to the 55 brush b^2 of the reverser. Brush b^2 of the reverser is connected to conductor 12, leading to the electromagnetic dash-pot around the

same, and thence by conductor 13 to the contact-plate c^{11} of the auxiliary resistance C . From this contact-plate leads a conductor 14 7 to the binding-post J , including a series field-magnet coil S , which is connected to the binding-post J' , and thence by conductor 15 is connected to the contact-plate c^{10} of the auxiliary resistance. Contact-plate c^6 is connected 75 by conductor 16 to the binding-post J^2 , and thence to the second series field-magnet coil S' to binding-post J^3 , which is connected by conductor 17 to the contact-plate c^5 of the auxiliary resistance. The binding-post J^3 is connected by conductor 18 to the contact f' of the potential switch F , which contact is normally open, as indicated. The brush D of the auxiliary resistance device is connected by a conductor 19 through the armature of the electro- 85 magnetic dash-pot E to the conductor 4. It is not deemed necessary to trace the circuits through these conductors under all conditions; as they are of a type substantially like that shown in my prior patent, No. 560,216, 90 and it is sufficient to say that as the switch-arm A' is moved to one side or the other the circuit is closed through the motor, so that the armature will rotate in one or the other direction, according to the movement of the arm, 95 and the brush D operates automatically to cut out more or less of the auxiliary resistance, and in cutting this out to also cut out more or less of the series field-magnet coils S S' , so that the greatest torque is exerted in starting the motor, and when running normally and under the usual load the brush D will rest upon the contact c^{11} and the motor operate as a true shunt-motor in a manner well understood. 105

In order to control the speed of the motor, as when it approaches the extremes of its movement or an intermediate landing or otherwise, I provide means for placing resistance in the armature-circuit and producing a parallel circuit to the armature, which circuit contains so much resistance that sufficient current will flow therethrough to cause the motor to slow up and, further, to insure that the motor shall work as a motor, even when 115 the descending maximum load on the car would tend to convert the motor into a generator. To do this, in the present instance I provide an auxiliary resistance N , arranged in shunt around the armature of the motor, 120 and in Fig. 1 I have connected with the binding-post I a post I'' , and from this leads a conductor 20 to one of the contacts g of the step-motion snap-switch G . Leading from this conductor 20 is a conductor 21, connected 125 to the segment a^6 , and the contact a^2 , operating in connection with said segment, is connected by conductor 22 to the contact g' of the snap-switch G . This latter contact g' is connected by a conductor 23 with the auxiliary armature-resistance N , the other end of which is connected by conductor 24 with binding-post I''' , which in turn is connected with the binding-post I' . With this construction 130

it will be seen that when the automatic stop snap-switch G is closed, as shown in the drawings, there is a branch or shunt circuit around the armature, including the resistance N, 5 and as this switch is arranged to be operated automatically or otherwise to open and close the circuit when, for instance, the car is traveling too fast or when, for instance, it approaches the extreme ends of its travel in the 10 well it will be seen that the motor will be caused to rotate more slowly whenever this switch is closed, and the speed of the elevator will therefore be lessened and even brought to rest, depending upon the relations of the 15 resistance-coil N to the armature-circuit. It will also be seen that when the arm A' of the switch is moved to a position so that the contact-plate a^2 bears on the segment a^3 while the contact a bears on one or the other of the 20 plates a^4 or a^5 there is also a closed shunt around the armature, including the resistance N, by which arrangement the operator on the car is enabled to close the shunt at any time to cause the motor to slow down without the 25 necessity of breaking the circuit or applying the brake. It will be observed that this auxiliary armature-resistance circuit is closed when the arm A' is in the position indicated in the drawings and the circuit of the armature is broken; but as the arm A' is moved to the right or the left, closing circuit with the contacts a^4 or a^5 , the shunt resistance-circuit is also closed; but when the arm is moved to the full extent the shunt is opened 30 and the motor operates under the usual conditions; but to cause it to slow it is only necessary for the operator to turn the arm A' partially toward its normal position sufficient to cause the contact a^2 to bear on the segment a^3 without breaking the circuit between the contacts a and a^4 or a^5 , as the case may be, and in this way a branch or parallel circuit to the armature is closed, including a resistance, and at the same time the movement 35 of the arm A' toward its normal position at the center allows brush D to move upward and include more or less of the resistance C in series with the armature, and the speed of the motor is gradually cut down to prevent a 40 sudden stoppage, such as might occur if the armature-circuit were instantly broken and the brakes applied.

While the arrangement thus far described has been found satisfactory in what may be 45 termed "light-duty" machines, in machines carrying heavy loads and traveling at high rates of speed I have found it desirable to control the speed between greater limits and to limit the current used in the circuit parallel to the armature as much as possible. This I accomplish by means of what I term an "extra field-coil" on the motor, which by means of the various switches may be placed in circuit parallel to the armature. This extra field-coil may be used alone for this purpose or in connection with an external resistance, which furnishes a convenient means

to adjust the extent of the operations of the various switches, which may have different effects upon the operation of the motor, and in Fig. 2 I have illustrated an embodiment of this feature of the invention, and in this figure the general circuits of the motor are lettered the same as in Fig. 1.

O represents the extra field-coil, one terminal of which is connected by conductor 25 to the binding-post H*, which is electrically connected to the binding-post H of the shunt field-magnet coil, while the other terminal of the resistance is connected by conductor 80 26 to the binding-post H**, and this binding-post may be connected through contacts a^2 and a^3 with the binding-post J when the extra field-coil is used alone without the external resistance; but in the present instance 85 I have shown the external resistance P, one terminal of which is connected by conductor 27 to the binding-post J, while the other terminal is connected by conductor 28 with contact a^2 , and the segment a^3 is connected by a 90 conductor 29 to the binding-post H**. Also connected to this latter binding-post is a conductor 30, including contacts g and g' , of the automatic stop snap-switch G, the contact g being connected to include a portion of the 95 external resistance P. With these connections it will be readily understood that when the automatic stop snap-switch G is operated to close the circuit a portion of the external resistance P is included in the circuit with 100 the extra field-coil O in shunt around the armature, and when the contact a^2 of the arm A' bears on the segment a^3 , the whole of the external resistance P is included in circuit with the extra field-coil. For convenience in 105 tracing them the external-resistance circuit is shown in dotted lines, while the extra field-coil circuit is shown in dot-and-dash lines. It will thus be seen that the extra field-coil and a portion or the whole of the external-resistance circuit is controlled by the automatic stop snap-switch or may be controlled by the operator on the car, and it is evident that other switches may be arranged in the line, so as to enable the circuit to be controlled—as, for instance, by the engineer in 110 the motor-room or by a governor or any of the well-known appliances used in connection with electric elevators for automatically opening and closing the switches. When 115 this extra field-circuit and external-resistance circuit are closed, the current flowing therethrough is limited by the sum of these resistances and the electromotive force of the armature, and this current acts as a brake 120 on the armature and at the same time adds to the magnetization of the field, the connections being such that the extra field-coil always assists the primary shunt field-magnet winding 3, and the speed of the motor is consequently diminished. As shown in the diagram, the closing of the automatic stop snap-switch G includes only a portion of the 125 external resistance P, and the total resistance 130

is therefore lower than when the circuit is closed by the main switch, including the whole of the external resistance, and therefore the current flowing through this circuit is larger, resulting in a greater speed reduction of the motor. It will be understood that not only can this extra field-coil with or without the external resistance be used in stopping or slowing the motor, but in case there is a heavy load, for instance, it may be used throughout the travel of the elevator, so that it will move at a slower rate of speed than normal. With these arrangements as herein indicated, which of course may be varied in detail, it will be seen that by properly proportioning the extra field-coil and external resistance with relation to the other parts of the motor the motor can be effectively slowed without breaking the circuit or applying the brakes, and the current flowing through the circuit may be such as to prevent the machine from sending back-current into the line or acting as a generator, and at the same time the current flowing through the extra field-coil may be sufficient to magnetize the motor up to saturation, so that the armature of the motor may run at a slow speed without drawing a heavy current from the supply-circuit. In connection with this arrangement of devices I have shown a potential switch F arranged in the armature-circuit, the coil of which is energized by a branch conductor 50 of relatively-high resistance, extending from the conductor 1 to the minus side 4. While the construction of this switch may be varied, the general principle is that when sufficient current flows through the coils to retain the armature in place the switch-lever F' is held in contact with the terminal f; but when the potential falls below the normal the armature is released and the switch-lever F' engages contact f', closing the circuit of the armature, thereby causing the machine to stop, and at the same time it will be observed that the shunt field-magnet coil 3 is unbroken, so that the field-magnets remain energized while the armature is in closed circuit. It is not deemed necessary to trace this circuit, as it is indicated by a dash superposed upon the other lines and can be readily traced.

Having thus described the general prin-

ples of my invention and set forth the preferred embodiments thereof, without limiting myself to the construction and arrangement illustrated, what I claim is—

55

1. The combination with a shunt-wound motor and circuits and connections for controlling the same, of an open shunt around the armature-terminals of the motor including a resistance device, and means for closing said shunt and including resistance between the armature-terminals, substantially as described.

60

2. The combination with a motor and circuits and connections for controlling the same, of a normally-open shunt around the armature-terminals of the motor, and an automatic stop-switch arranged to close the shunt between the armature-terminals to decrease the speed of the motor, substantially as described.

65

3. The combination with a motor, and circuits and connections for operating the same, of an extra field-coil in shunt around the armature-terminals of the motor arranged to magnetize the motor in the same direction as the shunt-field, and means for closing the extra field-coil on the terminals of the armature, substantially as described.

70

4. The combination with a motor and circuits and connections for operating the same, of an extra field-coil in shunt around the armature-terminals of the motor, an external resistance included in said shunt, and means for closing the shunt on the terminals of the armature, whereby the magnetization of the field is increased and the speed of the motor decreased, substantially as described.

75

5. The combination with a motor and circuits and connections for operating the same, of a potential switch arranged in the armature-circuit and adapted to interrupt the supply-circuit and to close the circuit of the armature upon itself while the shunt field-circuit is excited, substantially as described.

80

In testimony whereof I have signed my name to this specification in the presence of two subscribing witnesses.
